US00D857528S

(12) **United States Design Patent** (10) Patent No.: **US D857,528 S**
(45) Date of Patent: **** Aug. 27, 2019**

(54) **WATCH WITH DISPLAY**

- (71) Applicant: **Garmin Switzerland GmbH**, Schaffhausen (CH)
- (72) Inventors: **Marcus A. Moilanen**, Olathe, KS (US); **Peter J. Henne**, Overland Park, KS (US); **Aaron X. Molina**, Kansas City, MO (US)
- (73) Assignee: **Garmin Switzerland GmbH** (CH)
- (**) Term: **15 Years**
- (21) Appl. No.: **29/647,188**
- (22) Filed: **May 10, 2018**

U.S. Appl. No. 29/552,623, filed Jan. 25, 2016 entitled Watch With Display.

(Continued)

Primary Examiner — Sandra S Snapp

Assistant Examiner — Katherine Glennon

(74) *Attorney, Agent, or Firm* — Samuel M. Korte; Max M. Ali

(57) **CLAIM**

The ornamental design for a watch with display, as shown and described.

DESCRIPTION

FIG. 1 is a front perspective view of a watch with display according to the present invention;
FIG. 2 is a rear perspective view of the watch with display;
FIG. 3 is a top view of the watch with display;
FIG. 4 is a front view of the watch with display;
FIG. 5 is a bottom view of the watch with display;
FIG. 6 is a rear view of the watch with display;
FIG. 7 is a left side view of the watch with display; and,
FIG. 8 is a right side view of the watch with display.
The broken lines shown in FIGS. 1 through 8 represent portions of the watch with display that form no part of the claimed design.

1 Claim, 4 Drawing Sheets
